UNITED STATES PATENT OFFICE.

EDMUND J. BENNETT, OF FLINT, MICHIGAN.

BOTTLE-STOPPER.

SPECIFICATION forming part of Letters Patent No. 731,659, dated June 23, 1903.

Application filed November 21, 1902. Serial No. 132,189. (No model.)

To all whom it may concern:

Be it known that I, EDMUND J. BENNETT, a citizen of the United States of America, residing at Flint, in the county of Genesee and State of Michigan, have invented certain new and useful Improvements in Bottle-Stoppers, of which the following is a specification, reference being had therein to the accompanying drawings.

10 This invention relates to improvements in bottle-stoppers; and its object is to provide a closure for the mouth of bottles which requires no special form of bottle, which may be easily and quickly removed from the mouth 15 of the bottle to facilitate washing, but will yet be attached to the bottle to prevent the parts from becoming lost, and which is so constructed as to effectually close the bottle against leakage and at the same time will 20 allow the contents to escape by the simple act of depressing one of its parts.

It is also an object of the invention to provide a simple construction which is cheap to manufacture, easily assembled, and readily 25 taken apart for cleaning.

To this end the invention consists in providing a bushing member held in the mouth of the bottle by a bail-fastener and a nozzle member to fit within the bushing and having 30 a packing-washer at its lower end to engage the lower end of the bushing to prevent the escape of the contents of the bottle around the stem of the nozzle member.

It also consists in the novel construction, 35 arrangement, and combination of parts, all as hereinafter more fully described, reference being had to the accompanying drawings, in which—

Figure 1 is a side elevation of a device embodying my invention as attached to a bottle; Fig. 2, a central vertical section of the same; Fig. 3, a view illustrating the manner of operating the device to pour from the bottle; and Fig. 4 a perspective view, on a smaller 45 scale, of a bottle, showing the stopper removed and hanging by the bail-fastener at the side of the bottle.

As shown in the drawings, A is an ordinary smooth-necked bottle, and B a bushing member consisting of a tapered portion B' to extend into the mouth of the bottle, an upwardly-extending tubular portion B², and an out-

wardly-projecting integral collar or flange B³, provided with outwardly and downwardly extending integral ears B⁴ at opposite sides 55 for the attachment of the bail-fastener C. The said bail-fastener C is of the ordinary and well-known form, made of wire, and consisting of the bail portions C', having hooked ends to engage the openings in the ears B⁴, 60 and the lever portion C², which is attached to the neck of the bottle by the wire C³ and is connected to the bail portions in such a manner that when the bushing is inserted in the mouth of the bottle and the lever portion 65 turned the packing-ring D will be compressed between the flange B³ and the bottle, making a tight joint.

E is the nozzle portion of the stopper, consisting of a head E⁷, a shank E², and a stem E³, 70 the bushing being bored out to within a short distance of its lower end to fit the shank and the remainder of the way to fit the stem. The shank and stem of the nozzle portion being of different diameters, a shoulder E⁶ is formed 75 thereon, and the bushing being bored to fit these diameters a corresponding shoulder B⁵ is formed near the lower end of the bore of the bushing. Said nozzle is provided with an axial bore E⁴, extending to within a short distance of the lower end of the stem, where it is bored transversely to form lateral openings E⁵, as shown in Figs. 2 and 3, the stem being shown in Fig. 3 as turned to bring the openings at right angles to the position in which 85 they are shown in Fig. 2 for the purpose of better illustration, the nozzle member being free to turn in the bushing. A washer F, of leather or rubber, secured to the lower end of the stem by a screw, is provided to seat against 90 the lower end of the portion B' of the bushing and prevent any leakage around the stem. To hold the washer firmly to its seat and the nozzle projected from the bushing, a coiled spring G is sleeved on the stem, with its ends 95 engaging the shoulders E⁶ and B⁵, respectively, so that by pressing inward on the head, as shown in Fig. 3, against the action of said spring the stem is projected inward, moving the washer from its seat and uncovering the 100 openings E⁵ to allow the contents of the bottle to pass out through said openings into the bore of the nozzle.

By employing the bail-fastener to hold the

bushing in place the ordinary form of bottle may be used, and said bushing may be easily and quickly removed to clean the bottle and yet the parts be held intact and attached to the 5 bottle, so that they will not be lost. The stopper may also be readily taken apart for cleaning or to replace the washer by simply removing the screw which holds the washer to the stem.

10 Having thus fully described my invention, what I claim is—

1. In a bottle-stopper, the combination, with a bushing member having a tapered lower end to project into the bottle, of means for detachably securing the bushing member to the bottle, a nozzle member having a stem fitting within the bushing and provided with an axial bore and lateral openings, a spring to actuate the nozzle member sleeved on its stem within 15 the bushing, a packing-washer to engage and close the lower end of the bushing, and a screw to secure the washer to the lower end of the stem, whereby the nozzle member and spring 20

may be removed from the bushing by removing this screw. 25

2. In a bottle-stopper, the combination of a bushing member having a tapered lower end to project into the bottle, an outwardly-projecting flange on said bushing, ears on said flange, a wire bail-fastener consisting of the bail portions secured to the ears and the lever portion secured to the bottle and attached to the bail portions, a nozzle member having a stem fitting within the lower end of the bushing, a spring on the stem within the bushing, 30 a packing-washer, and a screw to secure the washer to the lower end of the sleeve in engagement with the lower end of the bushing to hold the nozzle member within the bushing against the action of the spring. 40

In testimony whereof I affix my signature in presence of two witnesses.

EDMUND J. BENNETT.
